(74) Attorney, Agent, or Firm—Black Lowe & Graham PLLC

(57) CLAIM

I claim the ornamental design for the footwear, as shown and described.

DESCRIPTION

FIG. 1 is a top left rear perspective view of footwear, embodying my new design;

FIG. 2 is a top perspective view of the footwear;

FIG. 3 is a right side elevational view of the footwear;

FIG. 4 is a left side elevational view of the footwear;

FIG. 5 is a front elevation view of the footwear;

FIG. 6 is a back elevational view of the footwear; and,

FIG. 7 is a bottom plan view of the footwear of FIG. 1.

The broken lines in the figures are for illustrative purposes only and form no part of the claimed design.

1 Claim, 5 Drawing Sheets
